(57) **CLAIM**

The ornamental design for a nail trimmer—rounded, as shown and described.

DESCRIPTION

FIG. 1 is a right side view of the nail trimmer—rounded showing the present invention in an opened position;

FIG. 2 is a left side view thereof;

FIG. 3 is a top view thereof;

FIG. 4 is a bottom view thereof;

FIG. 5 is a front view thereof;

FIG. 6 is a back view thereof;

FIG. 7 is a top, right side perspective view thereof;

FIG. 8 is a top, right side perspective view of the nail trimmer—rounded showing the present invention in a closed position;

FIG. 9 is a left side view thereof;

FIG. 10 is a top, right side perspective view of the nail trimmer—rounded showing the present invention with the cam lever rotated away into a store, open position;

FIG. 11 is a left side view thereof; and,

FIG. 12 is a right side view thereof.
